UNITED STATES PATENT OFFICE.

GORDON W. DUNN, OF MONTREAL, QUEBEC, CANADA, ASSIGNOR TO THE P & M COMPANY, OF CHICAGO, ILLINOIS, A CORPORATION OF ILLINOIS.

RAIL ANCHOR.

Application filed August 27, 1923. Serial No. 659,583.

To all whom it may concern:

Be it known that I, GORDON W. DUNN, a British subject, residing at Montreal, Province of Quebec, and Dominion of Canada, 5 have invented certain new and useful Improvements in Rail Anchors, of which the following is a specification.

My invention relates to rail anchors of the type comprising a clamping member in 10 the form of a casting or other fairly low grade metal, and a cooperating spring so mounted in relation to the clamping member as to be quite materially distorted upon the application of the anchor to the rail for 15 which it is designed. It is the principal object of my invention to provide a new and improved form and arrangement of parts in such a device as to provide the desired gripping effect, and at the same time to take 20 care of the expansion and contraction due to temperature changes; the clamping member being preferably of a form practically to enclose the spring and to hold the spring in position without the use of additional 25 securing means; and the metal of the clamping member being distributed so as best to carry the load therethrough from the rail to the tie. It is another object of my invention to provide such a construction and ar- 30 rangement of parts as will serve to skew the anchor horizontally with respect to the rail for maintaining a constant ratio of pressures on the several gripping portions of the anchor, as the pressure between the tie and the 35 rail is increased.

It is one of the objects of my invention to improve devices of this type in sundry details hereinafter pointed out. The preferred means by which I have accomplished my 40 several objects are illustrated in the accompanying drawing and hereinafter specifically described. That which I believe to be new and desire to cover by Letters Patent is set forth in the claims.

In the drawing,

Fig. 1 is a face view of the anchor ready for application to a rail, being broken away at one point for clearness of illustration.

Fig. 2 is a top plan view of the device of 50 Fig. 1, with only a fragmentary portion of the spring illustrated.

Fig. 3 is a view similar to Fig. 1 but showing the device in position upon a rail.

Fig. 4 is a view of the parts shown in 55 Fig. 3 as seen from the left in said figure,

with the device in position adjacent to a cross tie.

And, Fig. 5 is a view of the device as seen from the right in Fig. 3.

Referring to the several figures of drawing, in which corresponding parts are indicated by the same reference characters, 10 and 11 indicate cross bars joined by a horizontally disposed web 12 forming the body of the clamping device of my improved anchor, such parts being preferably integral in the form of a malleable iron casting. At one end, the cross bars are connected by a head 13, comprising horizontally disposed strengthening ribs 14 and vertically disposed strengthening ribs 15, the upper rib 15 merging into a jaw 16 projecting over the end portions of the bars 10 and 11 beyond the head 13. At the opposite end, the bars 10 and 11 are joined by a short bar 17 which 65 is located between ribs 18 and 19 forming extensions of the bars 10 and 11, respectively. At their upper ends the ribs 18 and 19 terminate in shoulders 20 and 21.

As is best shown in Figs. 1 and 3, a vertically extending rib or bar 22 is provided between the cross bars 10 and 11, such rib or bar 22 being formed integrally with the web 12. At the end of the device, corner plates 23 and 24 are provided, as is best 80 shown in Fig. 2, being formed integrally with the end portions of the cross bars 10 and 11, with the end portions of the short bar 17, and with the end portions of the ribs 18 and 19. These corner plates have their 85 under faces located at a slightly higher level than that of the upper edge of the rib or bar 22, the rib and plates forming bearings adapted normally to hold a bar 25 in position with one end underneath the plates and 90 with the other end extending above the level of the cross bars 10 and 11, preferably in close proximity to the under face of the jaw 16. With the bar 25 in such position, the longitudinal movement of the bar toward the 95 right in Fig. 1 is limited by the plate 17. The dimensions are preferably such as to permit the bar 25 to be inserted only by the application of a limited amount of pressure on the end of the bar for overcoming the 100 friction in forcing it past the edges of the plates 23 and 24, this having the result of preventing the bar normally from falling out of engagement with the body or shoe.

In the construction shown, the bar 25 is 110

designed to be formed preferably of spring steel so as to exert a very considerable upward pressure at its left hand end when such end of the spring is forced downwardly as illustrated in Fig. 3. The proportions of the parts are designed to be such, however, as to permit of the displacement of the end of the spring to the point indicated in Fig. 3 without danger of permanent distortion of the spring. Inasmuch as a high grade steel can be used to advantage in the bar 25, it will be appreciated that the permissible displacement and the resulting upward pressure may be made substantially as great as may be desired, this result being attained without unduly increasing the cost of the device as a whole, in view of the simplicity of the structure, the bar 25 being preferably only a straight bar which can be produced at a minimum cost.

With the device in the condition as shown in Fig. 1, with one end of the bar 25 inserted beneath the corner plates 23 and 24, the device is placed in transverse position across the bottom face of a rail, as 26, preferably adjacent to one of the cross ties 27. With the jaw 16 engaging the edge of the flange of the rail at the left, as shown in Fig. 3, the device is driven into the operative position as illustrated in that figure. As will be readily understood, the upstanding ribs 18 and 19 at the right and the upwardly extending end of the spring 25 at the left oppose the ready application of the device to the rail. The spring 25, however, is adapted to yield downwardly upon the application of sufficient force, and the jaw 16 is also adapted to yield slightly for providing the necessary distortion for permitting the shoulders 20 and 21 to snap past the edge of the flange of the rail at the right in said Fig. 3. The cross bar 11 in the construction shown is provided with a downward extension 28 in position to contact with the adjacent face of the cross tie 27, such extension 28 being preferably located slightly out of central position so as to permit of a limited skewing of the device horizontally with respect to a rail upon the application of the heaviest pressures to which the device is subjected under traffic conditions.

By reason of the extension 28 being located only a slight distance from the central point, the pressure is distributed in both directions to both ends of the shoe or body rather than being transferred to one end only of the device as would be the tendency if such extension were located at one end only. So far as I am aware, I am the first in the art to so arrange the abutment member of an anchor as to provide a definite unbalanced strain upon the opposite ends of an anchor, the arrangement being such that

as the pressure between the tie and the rail increases the pressures at the opposite ends of the anchor likewise increase in the same proportion with respect to the total pressure and at the same ratio with respect to each other.

As will be appreciated from an inspection of the drawing, the pressure of the spring 25 is applied in a downward direction upon the jaw 16. Inasmuch as this spring pressure may be made just as strong as may be desired, it will be appreciated that there is a very considerable margin of variation permissible in the dimensions of the device or in the dimensions of the rail base without there being any danger that the device cannot be tightened upon the rail. It will also be appreciated that as pressure is applied to the shoe or body of the device through the extension 28 so as to cause the shoe to cant lengthwise of the rail by turning slightly in clockwise direction in Fig. 4, for applying pressure upon the top and bottom faces of the flange, or so as to cause the shoe to skew horizontally with respect to the rail for applying pressure upon the side faces of the base at the opposite sides, such movement of the body will have a very slight effect upon the spring 25, even though very excessive pressure be applied upon the body for producing such gripping effect. In case the casting becomes elongated or otherwise distorted slightly through long usage under heavy traffic conditions, the body will still be capable of being moved into its effective gripping position for withstanding the heaviest pressures, and the spring will still continue to hold the device normally in a desired tightened condition when such extreme heavy pressures are absent. In the same way, the spring 25 will hold the body normally in proper position under any ordinary conditions of expansion or contraction.

By my invention, I have provided a two part anchor comprising a main portion in the form of a malleable iron casting, and a smaller portion in the form of a spring bar, the arrangement being such that the two parts can readily and quickly be assembled for shipment, and such that in use the casting member substantially encloses the spring member so as to protect it from injury. By my arrangement of parts, in which a spring is employed formed entirely independently of the shoe or body of the anchor, and adapted to take care of expansion and contraction of the device, to compensate for stretching of the casting in use, and further to compensate for the irregularities in the dimensions of the rail base which would otherwise make the device very difficult to fit properly upon the rail, practically all of the stresses are distributed through the casting member and have no

tendency to crystallize or otherwise unduly age the spring steel portion. The result is that the device is capable of use for a very long period without material deterioration.

By reason of my improved construction, in which the spring 25 is substantially enclosed within the heavy shoe comprising the major portion of the anchor, the application of the anchor to a rail may be effected without danger to the operator. In case the anchor is subjected to such excessive pressure in its application to the rail as to cause a fracture, such fracture will 10 of course take place in the malleable iron portion rather than in the spring steel portion. Such a fracture taking place in the low grade metal portion will ordinarily be much less serious from the standpoint of flying fragments than in the case of a fracture of a high grade spring steel part.

While I prefer to embody my device in the form illustrated in the drawing, it will be understood that I do not desire to limit myself to the particular form shown except so far as the same is specifically claimed, inasmuch as it is evident that various changes might be made without departing from the spirit of my invention.

30 I claim:

1. A rail anchor comprising a substantially rigid shoe in the form of a bar adapted to extend across the bottom face of a rail in contact therewith, having a jaw at 35 one end adapted to grip the base flange, and having a shoulder at the other end adapted to engage the outer face of the base flange at the opposite side of the rail, and a heavy spring formed separately from 40 the shoe and carried thereby, adapted to press said jaw downwardly upon the upper face of the base flange.

2. A rail anchor comprising a substantially rigid shoe in the form of a bar adapted to extend across the bottom face of a rail in contact therewith, having a jaw at one end adapted to grip the base flange, and having a shoulder at the other end adapted to engage the outer face of the 50 base flange at the opposite side of the rail, and a heavy bar spring formed separately from the shoe and supported by the shoe adjacent to said shoulder and extending therefrom longitudinally of the shoe with its 55 free end extending normally into close proximity to the under face of said jaw whereby when the anchor is applied to a rail the spring by leverage on the shoe causes the jaw to exert a heavy downward pressure 60 on the top face of the flange.

3. A rail anchor comprising a substantially rigid shoe in the form of a bar adapted to extend across the bottom face of a rail in contact therewith, having a jaw at 65 one end adapted to grip the base flange,

and having a shoulder at the other end adapted to engage the outer face of the base flange at the opposite side of the rail, spaced bearings carried by said bar, a heavy spring formed separately from the shoe and 70 supported loosely at one end by said bearings with the opposite end normally extending into close proximity to the under face of said jaw, and means for limiting the longitudinal movement of the spring in a 75 direction away from the jaw.

4. A rail anchor comprising a substantially rigid shoe in the form of a bar adapted to extend across the bottom face of a rail in contact therewith, having a jaw at one 80 end adapted to grip the base flange, and having a shoulder at the other end adapted to engage the outer face of the base flange at the opposite side of the rail, spaced bearings carried by said bar, a heavy spring formed separately from the shoe and supported loosely at one end by said bearings with the opposite end normally extending into close proximity to the under face of 85 said jaw, and means for limiting the longitudinal movement of the spring in a direction away from the jaw, the dimensions of the parts being such that said spring is normally held against withdrawal from the shoe.

5. A rail anchor comprising a substantially rigid shoe in the form of a bar adapted to extend across the bottom face of a rail in contact therewith, having a jaw at one end adapted to grip the base flange, and having a shoulder at the other end adapted to engage the outer face of the base flange at the opposite side of the rail, a bearing in the form of a rib extending at an angle 100 with respect to said bar, a heavy spring formed separately from the shoe and supported by said bearing, and a second bearing in spaced relation to said rib in position to receive the end of the spring beneath it for holding the spring in position 105 with the free end of the spring extending normally above the upper edge of the bar below said jaw.

6. A rail anchor comprising a substantially rigid shoe in the form of a bar adapted 110 to extend across the bottom face of a rail in contact therewith, having a jaw at one end adapted to grip the base flange, and having a shoulder at the other end adapted to engage the outer face of the base flange 115 at the opposite side of the rail, a bearing in the form of a rib extending at an angle with respect to said bar, a heavy spring formed separately from the shoe and supported by said bearing, and a second bearing 120 in the form of two horizontally disposed plates in spaced relation to each other and in spaced relation to said rib, with their adjacent edges converging towards the end of the anchor, said second bearing being in 125 130

position to receive the end of the spring beneath it, for holding the spring in position, with the free end of the spring extending normally above the upper edge of 5 the bar below said jaw.

7. A rail anchor comprising a substantially rigid shoe in the form of a bar adapted to extend across the bottom face of a rail in contact therewith, having a 10 jaw at one end adapted to grip the base flange, and having a shoulder at the other end adapted to engage the outer face of the base flange at the opposite side of the rail, a bearing in the form of a rib extending at 15 an angle with respect to said bar, a heavy spring formed separately from the shoe and supported by said bearing, a second bearing in the form of two horizontally disposed plates in spaced relation to each other 20 and in spaced relation to said first named bearing with their adjacent edges converging toward the end of the anchor, said second bearing being in position to receive the end of the spring beneath it for holding the 25 spring in position with the free end of the spring standing normally above the upper edge of the bar below said jaw, and means for limiting the movement of the spring longitudinally in the direction away from 30 the jaw, said jaw being in such position with respect to the bearing plates that the spring is capable of being withdrawn from the shoe only when centered between the plates and when subjected to a nominal pressure for 35 overcoming the friction between the bar and the bearing plates.

8. A rail anchor comprising a substantially rigid shoe in the form of a bar adapted to extend across the bottom face 40 of a rail in contact therewith, having a jaw at one end disposed at right angles with respect to the bar for gripping the base flange, and having a shoulder at the other end also at right angles with respect to the 45 bar, for engaging the outer face of the base flange at the opposite side of the rail, and a heavy spring formed separately from the shoe and carried thereby, adapted to press said jaw downwardly upon the upper face 50 of the base flange.

9. A rail anchor comprising a substantially rigid shoe having two bars in spaced relation, a jaw at one end adapted to grip the base flange of a rail, a shoulder at the 55 other end adapted to engage the outer face of the base flange at the opposite side of the rail, and a heavy spring formed separately from the shoe supported at one end in position between said two bars with its free end 60 extending normally above the upper edges of

the bars in position to be displaced upon the application of the anchor to a rail.

10. A rail anchor comprising a substantially rigid shoe in the form of a casting having two bars in spaced relation with a 65 web connecting the bars, a head formed on the ends of the bars and having a jaw adapted to engage the upper face of the base flange of a rail between the bars, a shoulder at the other end of the anchor adapted 70 to engage the outer face of the flange at the opposite side of the rail, and spring means stressed by the application of the anchor to a rail adapted to cause the jaw to press downwardly upon the upper face of the 75 flange.

11. A rail anchor comprising a substantially rigid shoe in the form of a casting having two bars in spaced relation with a 80 web connecting the bars, a head formed on the ends of the bars for providing a jaw adapted to engage the upper face of the base flange of a rail between the bars and having strengthening ribs merging with the jaw and said bars, a shoulder at the other end of the anchor adapted to engage the outer face of the flange at the opposite side of the rail, and spring means stressed by the application of the anchor to the rail adapted 85 to cause the jaw to press downwardly 90 upon the upper face of the flange.

12. A rail anchor comprising a substantially rigid shoe in the form of a bar adapted 95 to extend across the bottom face of a rail in contact therewith, having a jaw at one end adapted to grip the base flange of the rail and having a shoulder at the other end adapted to engage the outer face of the flange at the opposite side of the rail, and a downward extension on said bar in position to engage a cross tie, being located slightly out of central position for producing a limited skewing of the anchor horizontally with respect to the rail.

13. A rail anchor comprising a substantially rigid shoe in the form of a bar adapted to extend across the bottom face of a rail in contact therewith, having a jaw at one end adapted to grip the base flange of the rail and having a shoulder at the other end adapted to engage the outer face of the flange at the opposite side of the rail, and a downward extension on said bar in position to engage a cross tie, being located only 100 slightly out of central position with respect to the jaw and the shoulder for distributing the pressure through the anchor to both ends thereof at a constant ratio as such pressure varies under service conditions.

GORDON W. DUNN.
